UNITED STATES PATENT OFFICE.

HALSEY W. RUSSELL, OF MANCHESTER, NEW HAMPSHIRE, ASSIGNOR TO TUBELESS IRON COMPANY, OF MANCHESTER, NEW HAMPSHIRE, A CORPORATION OF MAINE.

SAD-IRON HEATER.

No. 901,744.

Specification of Letters Patent.

Patented Oct. 20, 1908.

Application filed June 19, 1908. Serial No. 439,339.

To all whom it may concern:

Be it known that I, HALSEY W. RUSSELL, a citizen of the United States, residing in Manchester, in the county of Hillsboro and State of New Hampshire, have invented a new and useful Improvement in Sad-Iron Heaters, of which the following is a specification.

This invention relates to sad-iron heaters, 10 of the general class of which the invention described in Letters Patent of the United States Numbered 847,116, and granted to me March 12, 1907, belongs; and it consists in the novel construction and arrangements of 15 parts hereinafter described, and illustrated in the accompanying drawings; the present improvement relating principally to a hinging mechanism and locking mechanisms whereby the work of the operator is facilitated and lessened, and the iron is applied to 20 the heater, heated thereon, removed therefrom and applied to the work with less manipulation than in the invention described in the patent above referred to.

25 In the drawings—Figure 1 is a front elevation of a sad-iron heater embodying my invention, applied to a table, with the iron applied to the heater, and with the iron and heater in a substantially horizontal position. 30 Fig. 2 is a section taken on line 2—2, Fig. 1, looking toward the left. Fig. 3 is a detail in end elevation of the air-mixer and adjacent parts of the heater. Fig. 4 is a detail in plan of a portion of the air-mixer and adjacent parts of the heater. In these four figures the parts are shown locked in a horizontal position for the purpose of heating the iron. Fig. 5 is a view partly in front elevation and partly in section of the device with 35 the iron applied thereto, the heater and iron being in a substantially vertical position, that being the position in which the iron is applied and removed.

Similar characters of reference indicate 40 corresponding parts.

Reference numeral 10 represents a portion of a table to which the offset arms 11 of a supporting-bracket are clamped by means of a suitable thumb-screw 12. The main portion 45 of this bracket consists of a substantially vertical frame 13 integral with the offset arms and substantially concavo-convex in horizontal section, the upper end of the frame being formed up into upwardly projecting

and substantially parallel ears 14 horizontally 55 bored to receive a pivot-pin 15, and formed up at 16 into parallel extensions which are connected by the integral curved flange-shaped rest 17. The extreme outer portion of the convex surface of the frame 13 is provided with two horizontal parallel projections or guides 18.

Pivottally connected with and supported by the bracket 13 by means of the pivot 15 in the ears 14 is the main frame or casing 19 65 of the perforated heater, the rear end 20 of said frame being flared or cone-shaped and adapted to receive a correspondingly shaped rotative sleeve provided with sector-plates 21 next the adjusting plate 22. The portion 70 20 constitutes the mixing-chamber, and a gas-cock 23 connects with the interior of the mixing-chamber and is provided with a lever or handle 24 which controls the supply of gas entering through the inlet-pipe 25. The construction of the parts 19 to 25 inclusive is, as far as described, the same as in the Letters Patent above referred to, and their operation is substantially the same as described in the said Letters Patent. There are however provided integral with the casing 19 a longitudinal fin 26 on the under side thereof (when the case is in its horizontal position) and a stop or lock 27 on its upper side, the objects of 80 which are below described.

85 28 represents the sad-iron secured at 29 to the burner 30, said burner being constructed as usual, except that it is provided on the inner surface of the side next the handle 31 with a groove 32 into which the fin 26 extends and thereby prevents rotation of the burner and sad-iron on the heater. The orifice 33 in the heel of the iron is provided with a projecting tooth 34 (Figs. 2 and 5) which is substantially in line with the stop 90 27 when the sad-iron and burner are applied to the heater.

95 When the device is in the position indicated in Fig. 5, the heater is nearly vertical, and the sad-iron 28 and burner 30, which are secured together as above described, are applied to the heater by dropping them over the upper end thereof by means of the orifices 33 and 35 in the heels of the sad-iron and burner respectively. As the iron and burner are 100 thus dropped the fin 26 enters the groove 32, and the lock 27, which is beveled or curved as shown in Fig. 5, slips over and by the tooth

34—there being room enough in the orifices to allow the necessary relative movement. When this has occurred the blunt rear edge 36 of the lock 27 rests against the inner side 5 of the tooth 34 and prevents the sad-iron from being removed without slightly swinging it on the heater, and the fin 26 prevents relative rotation. The iron, burner and heater are then moved from the substantially vertical position illustrated in Fig. 5 10 into the substantially horizontal position illustrated in the other figures, such movement being rendered possible by the pivotal connection 15. As the heater is thus moved down, its main portion 19 moves between the two guiding extensions 16, and rests on the flange-shaped rest 17, and at the same time the rear end of the handle 31 is guided between the two projections 18, and thus by 20 means of the locking-device 27, 34, and the projections 18, the burner and iron are held firmly in their approximately horizontal position. The object of the concavo-convex shape of the vertical frame 13 is to accommodate the peculiar shape of the mixing-chamber 20 when the parts are in the position indicated in Fig. 5.

As the sad-iron is heavy and is frequently removed from and applied to the heater, it is 30 important that there should be as few movements as possible during such removal and application. In my invention described in the Letters Patent above referred to, when the operator wished to remove the iron, he 35 reached down, turned the iron over, slid it off horizontally, and then carried the iron around on the table into an operative position. In my present invention, in order to remove the iron, the operator turns the 40 heater and iron into a vertical position, lifts the iron off (pressing it slightly to disengage the lock), and makes a quarter of a turn of the iron as he drops it onto the ironing-board. The turning of the iron while it is on the 45 heater amounts to about one quarter of a rotation in the present invention, while in the invention above referred to there is a half of a rotation.

The locking of the iron when it is applied to 50 the heater is automatic, as the sad-iron drops by gravity until the tooth 34 slips by the stop or lock 27, and then swings by gravity until the tooth is directly under the stop or lock, as illustrated in Fig. 5.

Having thus fully described my invention, 55 what I claim, and desire to secure by Letters Patent, is:—

1. In a sad-iron heater of the character described, a supporting-bracket adapted to be 60 clamped or secured to a table, a gas-heater pivotally connected with said supporting-bracket and adapted to move in a vertical plane, and a burner and sad-iron adapted to be supported by the heater, the frame of said 65 supporting-bracket being of shape to sustain

in connection with the pivot-pin the heater, burner and sad-iron either in a substantially vertical or a substantially horizontal position, for the purpose set forth.

2. In a sad-iron heater of the character described, 70 a supporting-bracket adapted to be secured or clamped to a table and comprising a frame provided with upward extensions connected by a flange-shaped rest, a gas-heater pivotally connected with said upward extensions and adapted to move in a vertical plane, and a burner and sad-iron adapted to be supported by the heater, whereby when the heater, burner and sad-iron are in a substantially horizontal position 75 80 the heater rests on said flange-shaped rest between said upward extensions.

3. In a sad-iron heater of the character described, 85 a supporting-bracket adapted to be secured or clamped to a table and comprising a frame substantially concavo-convex in horizontal section and provided with upward extensions connected by a flange-shaped rest, a gas-heater pivotally connected with said upward extensions and adapted to move in a vertical plane, and a burner and sad-iron adapted to be supported by the heater, whereby when the heater, burner and sad-iron are in a substantially horizontal position 90 95 the heater rests on said flange-shaped rest between said upward extensions, and when the heater is in a substantially vertical position its lower end which contains the mixing-chamber lies within the concavity in said frame.

4. In a sad-iron heater of the character described, 100 a supporting-bracket adapted to be clamped or secured to a table, a gas-heater pivotally connected with said supporting-bracket and adapted to move in a vertical plane, a locking-stop rigid with the upper surface of the heater when it is in a horizontal position, a burner, a sad-iron secured thereto, said burner and sad-iron being provided with suitable orifices for the reception 105 of the heater, the combined orifices being somewhat larger in diameter than the heater, and a tooth or projection extending from the lower end of the sad-iron when the same is elevated under the said locking-stop 110 whereby when the heater, burner and sad-iron are in a substantially vertical position said tooth moves by gravity under the said locking-stop, for the purpose set forth.

5. In a sad-iron heater of the character described, 115 a supporting-bracket adapted to be secured or clamped to a table and comprising a frame provided with upward extensions connected by a flange-shaped rest and with horizontal parallel projections or guides, 120 a gas-heater pivotally connected with said upward extensions and adapted to move in a vertical plane, and a burner and sad-iron adapted to be supported by the heater, whereby when the heater, burner and sad- 125 130

iron are in a substantially horizontal position the heater rests on said flange-shaped rest between said upward extensions and the handle of the sad-iron rests against said frame between the horizontal projections or guides.

In testimony whereof I have signed my

name to this specification in the presence of two subscribing witnesses.

HALSEY W. RUSSELL.
